UNITED STATES PATENT OFFICE.

CALEB D. PAGE, OF GREELEY, COLORADO.

ANCHOR DEVICE.

1,366,744.

Specification of Letters Patent. Patented Jan. 25, 1921.

Application filed February 9, 1920. Serial No. 357,221.

To all whom it may concern:

Be it known that I, CALEB D. PAGE, a citizen of the United States, residing at Greeley, county of Weld, State of Colorado, have 5 invented Improvements in Anchor Devices, of which the following description, in connection with the accompanying drawing, is a specification, like characters on the drawing representing like parts.

10 This invention relates to an anchoring device adapted to be driven into the earth, and when driven to resist upward strain, and the object of the invention is to provide an anchoring device of this nature which is 15 simple in construction, which can be used for a great variety of purposes, and which will effectively resist upward strain even if the ground into which the device is driven is more or less soft or sandy.

20 My improved anchoring device comprises a fluke portion adapted to be driven into the earth and a hold-down arm which extends at substantially right angles thereto. The fluke portion is formed with two opposed 25 relatively broad resisting surfaces and is so constructed that its cross-sectional area and its transverse dimension in any direction at a point adjacent the hold-down arm are at least as great as they are in any other point 30 in the length thereof. The hold-down arm is provided at its outer or free end with means to engage the article which is to be retained in place. Owing to the construction 35 of the fluke portion the driving thereof into the earth will have a tendency to pack the earth firmly about it. The upward strain on the end of the hold-down arm tends to turn the fluke portion in the earth in a direction transverse to the broad resisting 40 surfaces, and these surfaces come into play to effectually resist such turning movement and thereby hold the anchor firmly in place.

The anchoring device is adapted to be 45 used for a great variety of purposes among which may be mentioned for illustration the holding down of a bottom wire of a hog fence or the staking down of the walls of a tent.

50 In order to give an understanding of my invention, I have illustrated in the drawings some selected embodiments thereof which will now be described, after which the novel features will be pointed out in the appended claims.

Figure 1 of the drawings is a perspective

view showing one embodiment of my invention applied in holding down the bottom wire of a fence;

Fig. 2 is a side view of a different form of 60 the invention;

Fig. 3 is a top plan view of Fig. 2;

Fig. 4 is a section on the line 4—4, Fig. 2; 65

Fig. 5 is a side view of a different embodiment of the invention;

Fig. 6 is a front view of the device shown in Fig. 5;

Fig. 7 shows a still different embodiment of the invention.

Fig. 8 shows still another embodiment of 70 the invention.

As stated above, my improved anchor device comprises a fluke portion adapted to be driven into the earth, and a hold-down arm extending therefrom. The fluke portion is 75 provided with two relatively broad resisting surfaces having a parallel relation and the hold-down arm extends at right angles to such surfaces. The fluke portion will preferably be of uniform cross-sectional area 80 throughout its length, but in any event it is so constructed that the portion thereof adjacent the hold-down arm has a cross-section at least as large as that of any other portion thereof, so that when said fluke portion is 85 driven into the earth, the latter will be firmly packed about said fluke portion throughout its length.

In the embodiment shown in Fig. 1, the fluke portion of the anchoring member is indicated at 1 and the hold-down arm at 2. 90

This fluke portion is of uniform cross-section throughout its length and the two opposite sides thereof form relatively broad resisting faces, one of which is indicated at 95 3. The hold-down arm 2 extends from the fluke portion at substantially right angles to the faces 3, and it is preferably provided at its free or outer end with a suitable construction adapted to engage the device subject to upward stress. In the construction shown in Fig. 1, such device is the bottom wire 4 of a wire fence 5, and the outer end of the hold-down arm 2 is shaped to provide suitable engagement between said lower wire 100 and the anchoring device. This can conveniently be done by giving said arm a hook shape, thereby to provide a wire-receiving recess 6 on its under face which embraces the lower wire 4.

110 In using the device the fluke portion 1 will be driven into the earth at one side of

the fence, and in such position that when the hold-down arm 2 comes into substantial contact with the earth the bottom wire 4 of the fence which rests on or is close to the ground 5 will be received in the wire-receiving recess 6.

Owing to the fact that the fluke portion is of uniform cross-sectional area throughout its length, the driving thereof into the earth 10 will not loosen the earth, but will simply crowd the earth aside slightly so that the earth will remain firmly packed against the fluke portion throughout its entire length.

Any upward strain on the wire 4 brings 15 a corresponding upward strain on the hold-down arm 2, and this has a tendency to turn the fluke portion 1 in the earth, but the relatively broad faces 3 of said fluke portion develop sufficient resistance against the earth 20 to prevent such turning movement. It is important to note that with my improved anchor, the upward strain on the wire 4 does not produce an upward strain on the fluke portion in the direction of its length, 25 but tends to turn said fluke portion into an inclined position, which turning movement will be resisted by the relatively broad faces 3.

In using the anchor for holding down the 30 bottom wire of a hog fence, it will be desirable to place the anchors on the outside of the fence so that the hogs will not be able to root the anchors up. It will be understood, of course, that these anchors may be 35 placed as close together as desirable to properly hold the fence in position.

In Figs. 2 to 7, I have shown embodiments 40 of the invention which are adapted for other uses, such, for instance, as staking down tent walls. In the construction shown in Figs. 2, 3 and 4, both the fluke portion 11 of the anchor and the hold-down portion 12 of a T shape in cross-section and the fluke portion is provided with the relatively broad 45 face 13 and on the opposite side with a similar relatively broad face from the center of which a fin or rib extends. The fluke portion in Fig. 2 is shown as tapered slightly, but the portion of largest cross-sectional 50 area is situated at the upper end thereof adjacent the hold-down arm 8, and as a result the driving of the fluke portion into the earth merely crowds the earth aside so that when the fluke is driven the earth remains 55 firmly packed against the two relatively broad faces which develop the desired resistance against the earth due to upward strain on the hold-down arm. The hold-down arm 12 is provided at its outer end with a 60 beak 7 which is adapted to enter the eyelet 20 in the bottom of the tent wall 19, the point of the beak preferably extending slightly below the under face 8 of the hold-down arm 12. The upper end of the fluke 65 portion 11 is provided with the head portion

9 which is adapted to receive the hammer blows used in driving the anchor into the earth. The beak portion 7 is shaped to form the recess 16 which may receive either the eyelet in the tent wall or the loop in a tent 70 rope or any other fastening device which is to be subjected to upward strain. The end of the hold-down arm is also shown as provided with the additional hook portion 10 which may be used to anchor the guy rope 50 75 of a tent or other device, as shown in dotted lines.

In using this device for the purpose of staking down the walls of a tent, it is possible to drive the fluke into the ground 80 within the tent with the beak 7 extending through the eyelet in the bottom of the tent wall. The advantage of this is that since the anchor is situated entirely within the tent, the ground into which the fluke is driven will 85 be always dry and hard and will not be liable to be softened by rains as would occur if the fluke were driven into the ground outside of the tent.

In Figs. 5 and 6 I have shown a different 90 embodiment of the invention in which the device is made from a flat rolled bar which is bent into the general right angular shape to provide the fluke portion 21 and the hold-down portion 22. The fluke portion 21 has 95 the two opposite, flat, relatively wide faces 23 which produce the desired resistance to the turning movement of the anchor in the earth. The outer end of the hold-down arm 22 is twisted, as shown at 24, and such twisted 100 end is shaped to present the beak 27, notch 26 and hook portion 30. This beak and notch can be used for engaging the eyelet in the tent wall, the bottom wire of a fence or any other article which it is desired 105 to retain against upward movement, and the hook 30 to take the guy rope of the tent when not used to hold down the tent walls.

In Fig. 7 I have shown an embodiment 110 of the invention in which the fluke portion 31 is made of angle-iron and the hold-down arm 32 is made of a flat bar which is riveted or bolted to the angle-iron. The end of the hold-down is provided with the beak 37 and notch 36 to be engaged by the device which 115 is to be retained in position. In the construction shown in Fig. 7, the fluke portion is provided with the relatively broad faces 33 occupying a plane substantially at right angles to the length of the hold-down arm 120 32, and which faces serve to prevent any turning movement of the fluke in the ground 125 due to upward strain on the end of the hold down arm.

In Fig. 8 I have shown a different embodiment 130 of the invention wherein the hold-down arm is detachably secured to the fluke portion. In this construction the fluke portion is indicated at 41, and is made of angle iron, it having the flat broad faces 43 that

resist turning movement of the fluke in the earth. The hold-down arm 42 is detachably secured to the fluke portion by means of a key bolt 44 which is adapted to be inserted 5 in any one of a number of holes 45 formed in the fluke portion, thus providing for placing the hold-down arm at different elevations. The key bolt 44 is placed adjacent the lower side of the hold-down arm, and as 10 a result, when upward strain is applied to the outer end of said arm, the engagement of the heel end 48 of said arm with the faces 43 will prevent turning movement of the hold-down arm, so that said upward 15 strain will be transformed into a tendency to cause the fluke portion to turn in the earth, which tendency will be resisted by the surfaces 43.

In using this embodiment of the invention, the fluke portion may first be driven 20 into the ground at the desired spot and to the required depth, after which the hold-down arm may be detachably secured to the fluke portion in a position close to the 25 ground. If the ground is hard and firm it will not be necessary to drive the fluke portion to such a depth as if the ground is soft or sandy, and where the hold-down arm is 30 detachable from the fluke portion, it is possible to drive the fluke portion to a depth determined by the character of the ground, and then to apply the hold-down arm to the 35 driven fluke portion in a position close to the ground. On the other hand, where the fluke portion and hold-down arm are rigid or integrally connected, as shown in Figs. 1 to 7, it is always necessary to drive the 40 fluke portion clear into the ground in order to have the hold-down arm come close to the ground as is desired.

While I have illustrated herein devices in which the hold-down arm is at right angles to the fluke, yet the invention is not limited to the exact angle between the fluke 45 and the arm. All embodiments of the invention comprise a fluke portion adapted to be driven into the earth, and a hold-down arm extending laterally from the fluke portion, said fluke portion being either of uniform 50 cross-section throughout or constructed so that the portion of largest cross-sectional area will be adjacent the hold-down arm and having two relatively broad resisting faces extending throughout the 55 length of the hold-down arm and constructed to resist turning movement of the fluke

in the earth due to upward strain on the outer end of the hold-down arm. I regard it as of considerable importance to have the cross-sectional area of the upper portion of 60 the fluke at least as large as that of any other portion because with this construction the driving of the fluke into the earth will simply crowd the earth aside and cause it to be packed firmly against the fluke 65 throughout its entire length.

Various modifications other than those herein illustrated may be made in the construction of the device without departing 70 from the invention.

I claim:

1. An anchor device comprising a fluke portion adapted to be driven into the earth and a hold-down arm rigid therewith and extending laterally therefrom, said fluke 75 portion having two opposed relatively broad faces extending throughout the length thereof and arranged to resist turning movement of the fluke portion in the earth due to upward strain on the end of the hold-down arm, that part of the fluke portion adjacent the hold-down arm having a cross-sectional shape at least as large as that of any other portion thereof.

2. An anchor device comprising a fluke 85 portion adapted to be driven into the earth and a hold-down arm rigid therewith and extending laterally therefrom, said fluke portion being of uniform cross-sectional area 90 throughout its length and having two opposed relatively broad faces extending the full length thereof and arranged to resist turning movement of the fluke in the earth due to upward strain on the end of the hold-down arm.

3. An anchor device comprising a fluke portion adapted to be driven into the earth and a hold-down arm adjustably but rigidly connected with the fluke and extending laterally therefrom, said fluke portion having 100 two opposed relatively broad faces extending throughout the length thereof and arranged to resist turning movement of the fluke portion in the earth due to upward strain on the end of the hold-down arm, that part 105 of the fluke portion adjacent the hold-down arm having a cross-sectional shape at least as large as that of any other portion thereof.

In testimony whereof, I have signed my name to this specification.

CALEB D. PAGE.
